BINOCULAR CASE OR THE LIKE

Paul R. Maguire, Los Angeles, Calif., assignor to David P. Bushnell, Pasadena, Calif.

Filed Apr. 20, 1959, Ser. No. 55,566

Claims priority, application Japan Mar. 19, 1959

Term of patent 14 years

(Cl. D57—1)

Figure 1 is a rear perspective view of a binocular case or the like, showing my new design;

I claim:

The ornamental design for a binocular case or the like, substantially as shown.
